UNITED STATES PATENT OFFICE.

CHARLES L. HARRALSON, OF CASPER, WYOMING.

DRILL BIT.

Application filed August 3, 1924. Serial No. 730,923.

My invention relates to drill bits and more particularly to the drill bits described in my application filed Aug. 28, 1922, Ser. No. 584,917; and the object is to provide drill bits for drilling oil and other wells and which are provided with multiple wings or blades which are spiral in form, making the blades slanting so that the directly straight lift is to some extent avoided and the bit is thus compelled to rotate in an up or down stroke, thus throwing the mud from the central part outwardly and forming a mud plaster on the walls of the well and thus preventing the walls of the well from caving or ravelling. With such construction the bit will not be caked with mud. One side of the bit is cleaned going downward and the other side is cleaned going upward. Another advantage is that the outer points of the blades are approximately in the same elevation as the central part of the lower end of the bit and this construction makes and keeps the hole flat on the bottom and thus preventing the hole from becoming key-seated. The bit has been shown to be highly efficient in actual service conditions. Other objects and advantages will be fully explained in the following description and the invention will be more particularly pointed out in the claims.

Reference is had to the accompanying drawings which form a part of this application.

Fig. 1 is a side elevation of the bit, showing the points of the blades and the spiral formation of the blades. Fig. 2 is a bottom plan view of the blades.

Similar characters of reference are used to indicate the same parts throughout the several views.

The improved bit herein set forth is a multiple spiral blade bit and is shown provided with points 3, 4, 5, and 6, the points being slightly lower than the central part of the lower surface and the points are beveled. The blades are made in spiral form throughout the length of the bit, thus compelling the bit to rotate on up or down strokes and at the same time avoiding a direct vertical lift. The bit has the usual

shank connection 1. The spiral forms of the blades form spiral grooves in the bit. The object of the spiral blades or points is to keep the mud stirred and also to make the shoulders at the upper end of the bit serve 55 to keep the bit vertically disposed in the well so that it can readily be engaged by a fishing tool. The spiral form of the blades keeps the liquid agitated and prevents choking with mud; and since the blades are of 60 a uniform radius or diameter the wall of the hole will be of uniform diameter and straight.

The bit is provided with a face which has beveled cutting edges which project out of 65 the plane of the face at the external position. In Fig. 2, 7 indicates the water courses of the spiral form of the bit. The spiral form begins adjacent to the cutting edges and extends the whole length of the bit. 70 After the bit has been formed, the faces of the blades have to be dressed or sharpened in any suitable manner. The bit may be rolled, or forged, or cast of suitable metal. A portion of the bit is flat to be engaged 75 by the wrenches, as indicated by the surface 2. Three or more blades may be used on the bit. It must be understood that this invention does not relate to an auger bit, but to a bit that is suspended by a cable or which works with an up and down motion.

What I claim is,—

1. A cable tool impact drill bit having more than two integral spiral blades or wings extending back from the cutting end 80 of the bit, said blades or wings making less than a complete turn throughout the length of the blade.

2. A cable tool impact drill bit having more than two integral spiral blades or 85 wings and provided with a wrench square, a collar, and a tool joint at one end, said spiral blades or wings extending back from the cutting end to the wrench square, and making less than a complete turn throughout the 90 length of the blade.

In testimony whereof, I set my hand, this 5th day of August, 1924.

CHARLES L. HARRALSON.
